HUMIDIFIER

George Wyman Shearer, Montreal, Quebec,
CanadaApplication February 13, 1935, Serial No. 6,400
In Canada November 10, 1934

1 Claim. (Cl. 261—15)

The invention relates to humidifiers, as described in the present specification and illustrated in the accompanying drawing that forms part of the same.

5 The invention consists essentially in by-passing the flow of heating gases from a heating unit through a shell containing the water element with feed and delivery connections as pointed out in the claim for novelty following a description 10 in detail of the preferred construction.

The objects of the invention are to humidify the atmosphere in interiors of dwellings and public buildings and do so at a minimum cost; to insure even distribution of moisture under control of the user in regard to quantities and conditions and to provide comfort and health for the inmates.

In the drawing, Figure 1 is a side elevational view of a fragmentary part of a flue pipe and shell constituting the humidifier.

20 Figure 2 is a plan view of the same.

Figure 3 is a cross sectional view on the line 3—3 in Figure 1. Figure 4 is a vertical mid-sectional view.

25 Figure 5 is a vertical sectional view on the line 5—5 in Figure 1.

Like numerals of reference indicate corresponding parts in the various figures.

In this invention, by reference to the drawing, 30 it will be seen that the actual humidifier casing, indicated by the numeral 7 is mounted on a flue pipe 14 adapted to lead from the furnace, heating gases flowing with the waste gases from a furnace body through this flue.

35 The bands or straps 8 firmly secure this casing 7 to the pipe 14, and inside the casing 7 the humidifier discharge pipe 6 is secured and projects therefrom any suitable distance or can be led to separate room if desired, otherwise the 40 ends of the casing are closed.

The openings 10 and 11 are inlets to the humidifier casing and 12 is a return passage from the humidifier casing to the flue pipe beyond the damper 9, which means that the humidifier casing 45 is a by-pass to escape the damper 9.

The coil 2 is a spirally wound around the moisture discharge pipe 6, and projects from the discharge pipe at 1, the drain opening for the condensation being at 5 though the actual coil ends just beyond the discharge end of the said pipe 6, 5 and is connected to a suitable water supply.

This coil 2 continues to the valve 3 and terminates within the discharge pipe 6, adjacent to the inlet end, and in the spray nozzle 4 pointing in the direction of the discharge end of the said 10 pipe 6 where the moisture is expelled to the atmosphere. 13 represents a damper which, as shown by Fig. 5, is slidably arranged to close the outlet opening 10 and thereby regulate the bypassing of the gases. 15

The operation of this device is obvious from the description of the parts, for as a matter of fact, it is a humidifier where the flue pipe is used to heat a moisture discharge pipe, and this latter 20 contains a coil from the regular water service of a city or town or other community, and of course the heating gases flow from the fuel pipe through the inlets leading to what has been called the humidifier casing, otherwise, it is a closed form 25 of drum rigidly secured to the flue pipe and containing the coil that is to be heated to a high temperature, otherwise vaporized, and this vapor finds its way to the nozzle forming the termination of the coil pipe and from this nozzle the 30 spray or vapor shoots out into the humidifying and discharge pipe 6 and therebeyond. 35

I claim:

In a humidifier, a flue pipe having outlet and 35 return openings separated by a damper, a humidifier casing clamped about said flue pipe to confine the openings, a discharge pipe through said casing above said flue pipe, a water supply pipe coiled about said discharge pipe within the casing, said water supply pipe terminating in a 40 nozzle centrally mounted in said discharge pipe to project a stream of vapour therethrough and to the atmosphere. 45

GEO. W. SHEARER. 45
